United States Patent Office.

JAMES W. TRUMAN, OF MACON, GEORGIA.

Letters Patent No. 91,056, dated June 8, 1869.

IMPROVEMENT IN PENS.

The Schedule referred to in these Letters Patent and making part of the same.

To all whom it may concern:

Be it known that I, JAMES W. TRUMAN, of Macon, in the county of Bibb, and State of Georgia, have invented a new and improved Writing-Pen; and I do hereby declare that the following is a full, clear, and exact description thereof, which will enable others skilled in the art to make and use the same, reference being had to the accompanying drawing, forming part of this specification, in which—

Figure 1 represents an inverted plan view of my improved writing-pen.

Figure 2 is a longitudinal section of the same.

Similar letters of reference indicate corresponding parts.

The invention consists in arranging, under a split or non-split plate, which is shaped similar to the ordinary steel pen, an adjustable wire or rod, which, with its end, will form the writing-point of the pen. The end of this wire or rod can be fed forward when worn, and used again, until the wire is almost entirely used up, and the wire can then be readily replaced. The ink is held and flows freely between the plate and rod.

A, in the drawing, represents a plate, made of metal,

rubber, or other suitable material, shaped similar to the ordinary steel pen, but not necessarily split, and is fastened to a handle, B.

C is a wire, or other fine rod, arranged on the under side of the plate A, and guided in an eye, or eyes, a, formed on the same, as shown.

This wire or rod may be attached to the handle, or simply held under the plate, but I prefer to connect it with the handle, so that it may be screwed out when to be moved forward.

The point of the wire forms the writing-point of the pen, and will not be subject to the inconveniences of improperly-shaped steel or other plates now used.

Having thus described my invention,

What I claim as new, and desire to secure by Letters Patent, is—

A writing-pen, consisting of the split or unsplit plate A, and of the adjustable wire or rod C, substantially as described, to operate as specified.

JAS. W. TRUMAN.
